UNITED STATES PATENT OFFICE

HENRY ORSENIGO, OF MOUNT VERNON, NEW YORK

DESIGN FOR AN AUTOMOBILE BODY

Application filed March 20, 1929. Serial No. 30,525. Term of patent 3½ years.

To all whom it may concern:

Be it known that I, HENRY ORSENIGO, a citizen of the United States of America, residing at Mount Vernon, county of Westchester, State of New York, have invented a new, original, and ornamental Design for Automobile Bodies, of which the following is a specification, reference being had to the accompanying drawing, forming part thereof.

Fig. 1 is an elevation of an automobile body.

Fig. 2 is a perspective view of adjacent portions of a lateral side, the front side and of the ceiling of an automobile body interior; and

Fig. 3 is an elevation of the front side of the same.

That portion of the interior ornamentation not shown is exactly responsive to or identical in character with that disclosed.

The dominant feature of my design consists of the interior ornamentation as presented in Figs. 2 and 3.

I claim.

The ornamental design for an automobile body, as shown, and described.

HENRY ORSENIGO.
